UNITED STATES PATENT OFFICE.

JOHN ALBERT FISH, OF ST. JOHN, NEW BRUNSWICK, CANADA.

WATER-HEATING APPARATUS.

SPECIFICATION forming part of Letters Patent No. 351,859, dated November 2, 1886.

Application filed February 20, 1886. Serial No. 192,669. (No model.)

To all whom it may concern:

Be it known that I, JOHN ALBERT FISH, of St. John, Province of New Brunswick, Canada, have invented certain new and useful Improvements in Water-Heating Apparatus, of which the following is a specification:

This invention has for its object to provide a simple and efficient apparatus for heating and circulating water for warming purposes; and it consists in the several improvements hereinafter described and claimed.

Of the accompanying drawings, forming a part of this specification, Figure 1 represents a front elevation of the exterior of my improved apparatus. Fig. 2 represents a side elevation of the same. Fig. 3 represents a section on line $x-x$, Fig. 1. Fig. 4 represents a section on line $y-y$, Fig. 3. Fig. 5 represents a section on line $z-z$, Fig. 2. Fig. 6 represents a view of one of the sections of the diaphragm hereinafter described.

The same letters of reference indicate the same parts in all the figures.

In the drawings, a represents the inclosing casing of the brick-work, said casing containing a fire-box, b , grate c , and the bridge-wall e at the back of the fire-box. The bridge-wall is built with a ledge, e' , at its front side, a little above the grate, and on said ledge rests a receiving pipe or header, f , extending across the fire-box and through the side walls of the casing, as shown in Figs. 4 and 5. With said receiving-header communicate the lower sections or lengths of two series of pipes, g g , extending from the header f along the sides of the fire-box, and along the sides of the casing above the fire-box, and back and forth above the bridge-wall, to a pipe, h , which I term the "flow-header," extending across the upper part of the casing, the ends of said header being let into the side walls of the casing.

A series of vertical pipes, i , rise from the receiving-header somewhat higher than the furnace-door, and communicate with the lower lengths of a vertical series of pipes, j , extending back and forth lengthwise of the casing to the header h , and connected at their ends by return-bends. Water entering the receiving-header passes from thence through the pipes g , and through the vertical pipes i and pipe j to the flow-header h , and in its passage is exposed directly to the heat of the fire in the

fire box, and to the products of combustion in the casing above the fire-box, so that it enters the flow-header h in a heated condition.

From the flow-header extend distributing-pipes m , which convey the heated water to the rooms to be warmed. The cooled water is returned to the receiving-header by return-pipes n , entering return-headers o o , connected by elbows p p' with the ends of the receiving-header. The water is continuously circulated, rising from the receiving-header through the pipes g i j to the flow-header, and from thence to suitable radiators, and then back from the radiators through the return-pipes n and the return-headers o .

p represents a vertical diaphragm or semi-partition extending upwardly from the top of the bridge-wall partly to the top of the casing, and compelling the heat and products of combustion to pass directly upward from the fire-box around the portions of the pipes g and j at the front side of the diaphragm, and then downwardly around the portions of said pipes at the rear side of the diaphragm to the flue in the lower portion of the casing communicating with the chimney, as shown by the arrows in Fig. 3. All parts of the pipes g j are thus subjected to the action of the heat.

The diaphragm p is composed of plates or sections 2, (one of which is shown detached in Fig. 6,) each recessed to receive a row of the pipes g j . Said plates have ears 3 at their ends, through which pass vertical rods 4, held by lugs 5, affixed to the walls of the casing.

The pipes g and j are preferably made of wrought-iron, and the return-bends that connect said pipes are preferably of cast-iron, with right and left hand screw-threads.

It will be seen that the location of the receiving-header f at the front of the bridge-wall and near the grate, the arrangement of the lower sections of the pipes g g at the sides of the fire-box, and the arrangement of the vertical pipes i at the rear and of the lower sections of the pipes j over the fire-box insure the rapid heating of the water entering the receiving-header, said pipes being exposed to the best possible advantage to the direct action of the fire. The extension of the pipes g j through the casing above the fire-box and bridge-wall, together with the diaphragm p , insures the utilization of the heated products

of combustion passing from the fire-box. The diaphragm also supports the pipes and prevents them from sagging. Cocks *t t* in the elbows *p p* enable the water to be drawn off 5 from the entire system of pipes.

I claim—

1. In a water-heating apparatus, the casing having the fire-box, grate, and bridge-wall, combined with the receiving-header extending across the casing at the front side of the bridge-wall and above the grate, the pipes *g g*, 10 extending from said receiving-header along the sides of the fire-box and through the casing above the bridge-wall, the series of pipes *i*, extending upwardly from the receiving-pipe at the rear end of the fire-box, the series of 15 pipes *j*, communicating with the vertical pipes, and extending over the fire-box and through the casing above the bridge-wall, the flow-header located in the upper part of the casing and 20 communicating with the pipes *g j*, distributing-pipes extending from the flow-header, and return-pipes *n* and return-headers *o*, to return the water to the receiving pipe, as 25 set forth.

2. In a water heating apparatus, the casing having the fire-box, grate, and bridge-wall,

combined with the receiving-header extending across the casing at the front side of the bridge-wall and above the grate, the pipes *g g*, 30 extending from said receiving-header along the sides of the fire-box and through the casing above the bridge-wall, the series of pipes *i*, 35 extending upwardly from the receiving-pipe at the rear end of the fire-box, the series of pipes *j*, communicating with the vertical pipes, and extending over the fire-box and through the casing above the bridge-wall, the flow-header located in the upper part of the casing and 40 communicating with the pipes *g j*, the diaphragm extending upwardly from the bridge-wall around the return-pipes, distributing-pipes extending from the flow-header, and return-pipes *n* and return-headers *o*, to return the water to the receiving-pipe, as set forth. 45

In testimony whereof I have signed my name to this specification, in the presence of two subscribing witnesses, this 16th day of January, 1886.

JOHN ALBERT FISH.
